UNITED STATES PATENT OFFICE.

DAVID W. DOUGAN AND FRANK C. WATSON, OF PHILADELPHIA, PENNSYLVANIA.

STUFFING-BOX FOR PISTON-RODS.

SPECIFICATION forming part of Letters Patent No. 706,536, dated August 12, 1902.

Application filed September 3, 1901. Serial No. 74,187. (No model.)

To all whom it may concern:

Be it known that we, DAVID W. DOUGAN and FRANK C. WATSON, citizens of the United States, residing at Philadelphia, in the county of Philadelphia and State of Pennsylvania, have invented certain new and useful Improvements in Stuffing-Boxes for Piston-Rods, Valve-Stems, and the Like, of which the following is a specification.

10 Our present invention pertains to improvements in piston-rod stuffing-boxes, the construction and advantages of which will be hereinafter pointed out, reference being had to the annexed drawings, wherein—

15 Figure 1 is a top plan view, partly in section, of the box; Fig. 2, a front face view; Fig. 3, a vertical section view on the line 3 3, Fig. 1; Fig. 4, a sectional view on the line 4 4 of Fig. 1; Fig. 5, a longitudinal vertical sectional view; and Figs. 6 and 7 side and front elevations, respectively, of a modified form of the device.

20 The object of the present invention is to provide a superior stuffing-box, one in which a tight joint about the rod is effected and the rod thoroughly lubricated and one in which the parts may be readily assembled and firmly held in place.

25 In the drawings, A denotes the cylinder-head, and B the piston-rod. In the head there is mounted a sleeve C, formed with a central bearing for the rod and with a head D, which bears against the outer face of the cylinder. Longitudinal ways or channels E are formed in the sleeve, said ways communicating at their outer ends with an enlarged recess or chamber F, in which is mounted a coiled spring G. The main body of the box is formed of two sections, a lower section H and an upper section I. Each of said sections is formed with outward-extending interlocking ribs or flanges J, the outer faces whereof upon the upper and lower sides are formed with a beveled and inclined surface. (See 30 Figs. 3 and 4.) When the sections are assembled, these flanges form wedge-shaped dovetailed members, the narrower end of the wedge being forward or away from the cylinder. U-shaped blocks or clamps K are employed 35 to lock these members together. Inclined bearing-surfaces are formed upon the inner faces of these members, the inclination being

the reverse of that of the ribs, so that as the blocks are slipped on and moved inwardly along the ribs the parts of the box are securely 55 and rigidly held together.

40 A suitable metallic packing L is interposed between the head D of the sleeve and the inwardly-projecting ribs M of the box. As will be seen upon reference to Fig. 5, the face of 60 the ribs against which the packing bears is inclined or concave, so that the steam-pressure exerted on the packing would tend to force the packing in against the rod. The same action is secured by the spring. A second metallic packing N is mounted in the outer end of the box. Felt sections O P are 65 mounted in the box and are held in position by the metallic plates or half-rings Q and R, a pair being employed for each felt section. 70 These plates form a chamber for the reception of the oil, which, passing down around the rod, finds its way to the lower edges of the felt sections through a groove or channel S, formed in the lower box-section. An outer 75 metallic bushing-ring T surrounds the rod and bears against the outer metallic packing N, and a shoulder formed on the ring also bears against the outer face of the box adjacent to the rod.

80 Stud-bolts U are employed for securing the box as a whole to the cylinder-head and also as a means for holding the clamps in place and securing the face-plate V in position. As will be seen upon reference to Fig. 1, the 85 bolts are screwed into the cylinder and pass forwardly through the U-shaped clamping members K, sufficient clearance being left for this purpose. The outer ends of the bolts are threaded, and nuts W mounted thereon 90 bear directly against the clamps, serving to force them to place, and thereby binding the parts of the box together and also forcing the box as a whole closely to its seat in the head D of the sleeve C. Nuts W, as will be seen 95 in Fig. 1, are externally threaded and pass through openings X left in the face-plate V. Nuts Y are mounted on said threaded portion, and when screwed to place hold the face-plate in position. To more securely hold the 100 upper and lower edges of the plate in place, supplemental bolts Z are employed, the bolts passing into the body of the box.

A sliding cover a is mounted on the upper

2
half of the box over the oil-opening therein. A spring *b*, secured to its under side, serves to normally hold the cover closed; and lugs or stops *c* and *d*, one carried by the cover 5 and the other extending up from the box, prevent entire removal of the cover.

In Figs. 6 and 7 a modified form of construction is shown. Instead of having the cover lie in a horizontal plane the upper section 10 of the box is extended upwardly and outwardly, forming a neck *e*, a sliding cover *f* being mounted thereon.

Having thus described our invention, what we claim is—

- 15 1. In combination with a two-part stuffing-box, clamps to secure said parts together; and means for securing the box in position, said means likewise acting on the clamps and causing the same to become effective, substantially as described.
- 20 2. In combination with a cylinder; bolts extending out therefrom; a longitudinally-separable packing-box; clamps for securing the box together; and nuts mounted on the bolts, said nuts bearing on the clamps and serving to hold the box in position.
- 25 3. In combination with a cylinder, bolts extending out therefrom; a longitudinally-separable packing-box; wedging-clamps for securing the parts thereof together; and nuts mounted on the bolts acting to force the clamps to place and to hold the box in position.
- 30 4. In combination with a cylinder; bolts extending out therefrom; a longitudinally-separable packing-box, each section thereof having abutting flanges which when the parts are assembled form dovetailed wedges; wedging-clamps fitting on said flanges, and nuts mounted on the bolts acting to force the clamps to place and to hold the box in position.
- 35 5. In combination with a cylinder, bolts extending out therefrom; a longitudinally-separable packing-box; each section thereof having outwardly-projecting ribs adapted to abut with those of the adjacent section; wedge-shaped clamps longitudinally movable on the ribs; and nuts mounted on the bolts and bearing on the clamps moving the same inwardly thereby drawing the sections together and at the same time securing the box in place.
- 40 6. In combination with a cylinder; bolts extending out therefrom; a longitudinally-separable stuffing-box; wedging-clamps for securing the sections of the box together; nuts mounted on the bolts and bearing on the clamps; a face-plate for the box; and means for securing the face-plate in position.
- 45 7. In combination with a cylinder; bolts extending out therefrom; a longitudinally-separable stuffing-box; wedging-clamps for securing the sections together; nuts mounted on the bolts and bearing on the clamps; a face-plate for the box, said plate having openings through which the bolts and nuts pass; and a second set of nuts secured upon the outer threaded face of the first set, said second set bearing on the face-plate and holding the same in position.
- 50 8. In combination with a cylinder; a sleeve mounted therein; having passages for steam; a spring mounted in the end of the sleeve; a stuffing-box; means for securing said box in position; an oil-reservoir formed in the box; and metallic packing interposed between the rounded inner face of the box and the outer end of the sleeve.
- 55 9. In combination with a cylinder; a sleeve mounted therein and having passages for steam therethrough; a spring mounted in the outer end of the sleeve; a stuffing-box secured to the cylinder over the sleeve; and a metallic packing interposed between the rounded inner face of the box and the end of the sleeve.
- 60 10. In combination with a cylinder; a longitudinally-separable stuffing-box; means for securing it together; metallic packing mounted in the outer ends of said box; sections *Q* and *R* mounted in the box and forming an oil-reservoir intermediate the same; fibrous packing adjacent to said sections; and means for securing the box to the cylinder.
- 65 11. In combination with a cylinder; a longitudinally-separable stuffing-box; means for securing it together and to the cylinder; an oil-chamber formed in said box; and a sliding cover mounted on the box, said cover being provided with means for preventing its entire removal and likewise with means for maintaining it in a normally closed position.
- 70 12. In combination with a cylinder; a longitudinally-separable stuffing-box; wedging-clamps for securing the sections together; bolts extending out from the cylinder and passing freely through the clamps; a bushing-collar *T*; a face-plate; nuts mounted on the bolts and bearing on the clamps; and a second set of nuts mounted on the threaded exterior of the first set of nuts and serving to clamp the face-plate in position.

arable stuffing-box; wedging-clamps for securing the sections together; nuts mounted on the bolts and bearing on the outer ends of the clamps; a face-plate for the box, said plate having openings through which the bolts and nuts pass; and a second set of nuts secured upon the outer threaded face of the first set, said second set bearing on the face-plate and holding the same in position.

75 13. In combination with a cylinder; a sleeve mounted therein; having passages for steam; a spring mounted in the end of the sleeve; a stuffing-box; means for securing said box in position; an oil-reservoir formed in the box; and metallic packing interposed between the rounded inner face of the box and the outer end of the sleeve.

80 14. In combination with a cylinder; a sleeve mounted therein and having passages for steam therethrough; a spring mounted in the outer end of the sleeve; a stuffing-box secured to the cylinder over the sleeve; and a metallic packing interposed between the rounded inner face of the box and the end of the sleeve.

85 15. In combination with a cylinder; a longitudinally-separable stuffing-box; means for securing it together; metallic packing mounted in the outer ends of said box; sections *Q* and *R* mounted in the box and forming an oil-reservoir intermediate the same; fibrous packing adjacent to said sections; and means for securing the box to the cylinder.

90 16. In combination with a cylinder; a longitudinally-separable stuffing-box; means for securing it together and to the cylinder; an oil-chamber formed in said box; and a sliding cover mounted on the box, said cover being provided with means for preventing its entire removal and likewise with means for maintaining it in a normally closed position.

95 17. In combination with a cylinder; a longitudinally-separable stuffing-box; wedging-clamps for securing the sections together; bolts extending out from the cylinder and passing freely through the clamps; a bushing-collar *T*; a face-plate; nuts mounted on the bolts and bearing on the clamps; and a second set of nuts mounted on the threaded exterior of the first set of nuts and serving to clamp the face-plate in position.

In testimony whereof we have signed our names to this specification in the presence of two subscribing witnesses.
